UNITED STATES PATENT OFFICE.

HENRY EDMUNDS, JR., OF NEW YORK, N. Y., ASSIGNOR TO THOMAS J. MONTGOMERY, OF BOSTON, MASSACHUSETTS.

CIRCUIT-CONNECTION FOR ELECTROLIERS.

SPECIFICATION forming part of Letters Patent No. 290,407, dated December 18, 1883.

Application filed April 5, 1883. (No model.)

To all whom it may concern:

Be it known that I, HENRY EDMUNDS, Jr., of the city, county, and State of New York, have invented an Improvement in Circuit-
5 Connections for Electroliers; and the following is declared to be a description of the same.

This invention relates to the wiring and the forming of circuit-connections upon chandeliers, electroliers, special fixtures, &c., either
10 when used upon new articles or upon what is termed "adapted work."

I employ a connection to the gas-pipe at the ceiling of a room, and a hook and block or button of non-conducting material connected therewith for suspending the chandelier, and I use insulating-blocks in connection with these suspending devices, upon which the circuit-connections, circuit-fuses, or safety-switches for the electrolier are placed, and I carry
15 through these blocks the direct wire for lighting; and in the junction-box, from which radiate the tubular arms of the chandelier, I take wires to each lamp and connect them with this direct conductor. The return-wires are brought, one from each light, through their respective switches to the distribution-box, and they are by preference grouped in pairs and led up the tubular stem of the chandelier to the safety switch-block, and here each separa-

rate wire is secured to a binding-screw and connected by a metal plate and circuit-fuse to a union-ring, from which one wire leads to a binding-screw and circuit-fuse in the ceiling-block, and so away to the line. By this construction I am enabled to insulate the chandelier completely from all metallic contact that is likely to cause a leak of current or a false circuit; and by this arrangement of circuits I can control each incandescent lamp inde-
pendently from any other lamp on the electrolier, and where any circuit-fuse is melted it only affects the lamp in the branch circuit containing such fuse, and a new circuit-fuse can be put in without disturbing any of the wiring.

In the drawings, Figure 1 is an elevation of a two-light electrolier. Fig. 2 is a section of the ceiling-block, suspending-bail, and insulating-roller, and an elevation and partial section of the suspending-block. Fig. 3 is an

elevation of the ceiling-block and cross-section of the suspending-block. Fig. 4 is a plan of the suspending-block, and Fig. 5 is a section of the distribution-box at the junction of the tubular arms of the electrolier.

The electrolier B may be of any desired construction or ornamentation, and have any desired number of incandescent lamps, A, my system of circuit-connections being equally adapted to all.

The electrolier is suspended from the gas-pipe in the ceiling as follows: A coupling, a', having projecting lugs a², is screwed on the gas-pipe a", secured in the ceiling. Passing through these lugs a² is an axis or pin, b², carrying the insulating-roller b³, which is, by preference, made of porcelain, although other similar material will answer equally well. A bail, c', is suspended from this roller, its ends passing through the fuse-block D, and through a metal ring held by nuts c². In the top of this block D is a thimble, d, secured by screws to said block, and into this thimble the tubular stem e of the electrolier is screwed, as seen in Fig. 3. The head-block C and fuse-block D each have an extra case of plain or ornamental sheet metal corresponding in appearance with the electrolier, and the same can be removed to give access to the circuit-connections.

The distribution-box E is, by preference, a circular cup-shaped casting, into the upper part of which the tubular stem e of electrolier is screwed, and into the sides of which the tubular branches e' are screwed. Its lower side is open, and a plate, f, with a spindle f', is screwed to the same, and this spindle has screwed upon it the ornamental end g of the electrolier.

The circuit-connections are made as follows: There is a recess in the ceiling-block C at C', and this contains a plate of metal, g', and binding-screws 5 6, and the main or direct circuit-wire b comes from the ceiling through a hole in the block C to the binding-screw 5, the current passing through the wire b to said screw 5 and to plate g', from thence to binding-screw 6, and by a second wire, b, to binding-screw 8, plate g², and binding-screw 9. These binding-screws 8 and 9 and plate g² are upon the top

of the fuse-block D. From binding-screw 9 the circuit-wire 4 descends through the tubular stem e of the electrolier to the distribution-box E. At this point independent direct circuit-wires leading to each incandescent lamp are connected to the circuit-wire 4, thus completing the positive connection to the lamps. The return-wires 2 from the incandescent lamps A are carried through the switch H, 15 through the tubular branches e' to the distribution-box E, and there I prefer to connect them in pairs, and so conduct them up the chandelier or electrolier and to the outside of the fuse-block D through the holes h. Upon the fuse-block D each of the wires 2 is connected to a binding-screw, 7, and electrode or plate v; and Figs. 2, 3, 4, and 5 are represented as wired for and belonging to an electrolier having six incandescent electric lights, the plan 20 view, Fig. 4, being hexagonal, but the number may vary. Around the block D is an electrical "union-ring," v', and each circuit-wire, 2, is electrically connected with it through the binding-screws 7, electrodes or plates v, and 25 circuit-fuses t, thus putting an independent safety-switch or "circuit-fuse" in the branch electric circuit of each incandescent lamp. From this union-ring v' the wire b' passes from the binding-screw 12 up into a recess, e', in 30 the ceiling-block C, and is connected with the binding-screw 17, and from this binding-screw 17 the electric current passes to the electrode or plate v'', circuit-fuse t'', electrode or plate v'', binding-screw 17, (see Fig. 3,) and so away 35 to the return-line wire.

The great advantage of connecting the circuit-wires and using circuit-fuses in each branch circuit is that the burning out of one fuse only affects one lamp, and the connections 40 being upon the surface of blocks, as set forth, are easily got at to replace the fuses and also to adjust the wires, if required.

These improvements in circuit-connections for electroliers are especially useful in what is 45 known as "adapted fittings" where gasoliers or chandeliers are formed into electroliers, retaining the fixtures as a whole, but adapting them for electrical lamps.

I remark that the fuse-block D is to be furnished with as many circuit fuses and connec- 50

tions from the return-wires 2 as there are incandescent lamps upon the electrolier.

I claim as my invention—

1. The combination, in an electrolier, of the ceiling-block C, bail e', for suspending the electrolier, the fuse-block D, at the upper part of the tube e, the distribution-box E, at the junction of the tube e and branches, and incandescent lamps A, and circuit-wires passing through the pipes, substantially as and for the purposes set forth.

2. The combination, with an electrolier, of the pipe a'', a coupling-tube, a', screwed upon the pipe a'', projecting lugs a'', axis b'', insulating-roller b'', bail e', block D, through which the bail passes, and the nuts e'', for suspending the electrolier, substantially as and for the purposes set forth.

3. In an electrolier, the combination, with the ceiling-block C, having openings C' C'', of the plate g' and binding-screws 5 6, within such openings, and forming connections for the direct-circuit wire, and the binding-screws 7, electrodes or plates v'' v'', and circuit-fuse t'' in such ceiling-block, and forming the circuit-connections for the return-circuit wire 2, substantially as set forth.

4. In an electrolier, the combination, with the fuse-block D, its bail e', and the plate d, to which the tubular stem e of the electrolier is secured, of the binding-screws 7, electrodes or plates v, circuit-fuses t, union-ring v', and binding-screw 12, around the fuse-block and forming the circuit-connections for the branch circuit-wires, and the binding-screws 8 and 9, and plate g'', upon said block D, for forming the circuit-connections to the direct circuit-wires, substantially as set forth.

5. An electrolier having tubular stem and branches with circuit wires and lamps, in combination with a suspending-bail and insulating roller or support for such bail, substantially as set forth.

Signed by me this 29th day of March, A. D. 1883.
